[57] CLAIM

The ornamental design for a rear view mirror, as shown and described.

DESCRIPTION

FIG. 1 is a perspective view of the front, top and one side of a rear view mirror showing my new design which is mountable on the left side of a motor vehicle; FIG. 2 is a front elevational view thereof;

FIG. 3 is a top plan view thereof;

FIG. 4 is a rear elevational view thereof in inverted condition;

FIG. 5 is a bottom plan view thereof;

FIG. 6 is an elevational view of one side thereof;

FIG. 7 is an elevational view of the other side thereof;

FIG. 8 is a perspective view of the front, top and one side of a rear view mirror showing a second embodiment of my new design, the sole difference being that it is mountable on the left side of a motor vehicle;

FIG. 9 is a front elevational view of the embodiment of FIG. 8;

FIG. 10 is a top plan view of the embodiment of FIG. 8;

FIG. 11 is a rear elevational view of the embodiment of FIG. 8 in inverted condition;

FIG. 12 is a bottom plan view of the embodiment of FIG. 8;

FIG. 13 is an elevational view of one side of the embodiment of FIG. 8;

FIG. 14 is an elevational view of the other side of the embodiment of FIG. 8.
